PATENTED

DEC 3 1867

Fig:1.

Fig.2.

United States Patent Office.

CHRISTOPHER L. FRINK, OF ROCKVILLE, CONNECTICUT, ASSIGNOR TO E. H. ROBINSON, E. I. SMITH, AND ROBERT L. FRAIR, OF THE SAME PLACE.

Letters Patent No. 71,599, dated December 3, 1867.

IMPROVEMENT IN DEVICES FOR SMOOTHING CLOTH.

The Schedule referred to in these Letters Patent and making part of the same.

TO ALL WHOM IT MAY CONCERN:

Be it known that I, CHRISTOPHER L. FRINK, of Rockville, in the county of Tolland, and State of Connecticut, have invented, made, and applied to use a certain new and useful Improvement in Smoothing and Equalizing Cloth Previous to Giggling; and I do hereby declare the following to be a full, clear, and exact description of the said invention, reference being had to the annexed drawing, making part of this specification, wherein—

Figure 1 is a vertical section of my said machine, and

Figure 2 is a plan of the same.

Like letters denote the same parts.

After cloth has been fulled, there are creases in it and wrinkles, besides which the shrinkage and tension in the fulling often produce great inequalities in the width. It has been usual heretofore to subject the cloth to the action of the gig-machine after the fulling; and in order to stretch the cloth widthwise and remove the creases and mill wrinkles, it has been usual to apply temples upon the wrong side of the cloth as it goes through the gig. An attendant is required to raise these temples as they pass the teasels, or else the cloth will be injured by the scraping and scratching of the teasels against the cloth where pressed upon by the temples. Neglect of the attendant often causes pieces of cloth to be injured in this manner.

The object of my invention is to entirely remove the mill creases and folds, equalize the width of the cloth, and produce a perfectly smooth and flat piece of cloth, that can be run through the gig without the use of temples. To effect this object I moisten or heat the cloth and wind it upon a roller with sufficient pressure to effect the removal of the said creases, and the cloth, when allowed to dry, or nearly so, upon said roller, becomes of a very smooth character, adapted to the finishing operations.

In the drawing, *a* represents the frame of my machine, supporting the main cylinder *b*, that is rotated by gearing, *c*, and a pulley, *d*, for a belt, or in any other convenient manner. *e* is a stationary hollow cylinder heated by steam introduced by a pipe, *f*, and *g* is a pipe to convey away the water of condensation. *h* is a trough in which is a steam-pipe, *i*, which is perforated to moisten the cloth as it is passed over said trough *h*, in cases where the cloth may be too dry for the subsequent operations. *l* is a bar over which the cloth passes, and said bar also forms the hinge for the swinging frame that carries the winding-roller; *m m* being the side bars of said frame, and *n* the front bar. *o o* are the bearings for the cloth-roller *p*, said bearings having holes at their ends for the rods or bars *l n*. These bearing-bars *o o* for the roller *p* can be slidden on *l* and *n*, nearer together or further apart, and clamped in place by set-screws, and they become the gauge for the width of the cloth, and are adapted to receive longer or shorter rollers. To the bar *n* weights are hung to produce the necessary pressure of the cloth-roller *p* on the main cylinder *b*.

It will now be understood that the end of a piece of cloth is to be passed into the machine below the cylinder *e*, over the bar *l*, and evenly wound upon the cloth-roller *p*. The main cylinder is then revolved by power and the cloth gradually drawn in and wound upon the roller *p*. The attendant smooths the cloth as it passes over the trough *h*, and also upon the bar *l*, at the same time stretching it to the proper width and position so that the cloth is wound smooth and uniform upon the roller *p*.

This operation is performed with rapidity, and the cloth being in a moist and warm state when wound up, entirely loses all creases, folds, and inequalities. Several pieces may be wound upon one roller, if desired, as the frame and roller *p* rise as the roll of cloth increases.

What I claim, and desire to secure by Letters Patent, is—

The movable bearing-bars *o* for the roller *p*, applied substantially as specified, in combination with the main cylinder *b* and heated cylinder *e*, as and for the purposes set forth.

In witness whereof, I have hereunto set my signature, this eighteenth day of April, 1867.

C. L. FRINK.
